UNITED STATES PATENT OFFICE.

ROBERT W. LOGAN, OF INDIANAPOLIS, INDIANA, ASSIGNOR TO FERNANDIZE
M. SIMMONDS AND GEORGE K. SCHOFIELD, BOTH OF SAME PLACE.

RAIL FOR DASH-BOARDS.

SPECIFICATION forming part of Letters Patent No. 339,307, dated April 6, 1886.

Application filed September 11, 1885. Serial No. 176,774. (No model.)

To all whom it may concern:

Be it known that I, ROBERT W. LOGAN, of the city of Indianapolis, county of Marion, and State of Indiana, have invented certain new and useful Improvements in Detachable Hand-Rails for Dash-Boards, of which the following is a specification.

Heretofore in the manufacture of vehicles rails for the dash-boards have been used only on the better class of work, on account of the expense consequent upon their attachment by the ordinary method, which has usually been to weld said rail at several points to the frame of the dash, thus making it necessary to stitch the cover onto said frame by hand, which is both slow and expensive.

The object of my said invention is therefore to provide a rail which can be quickly and easily attached to any dash-board after it is otherwise complete, and also easily detached when it is desired to do so, (as when it needs replating,) thus making a more desirable rail, and one which can be used on the cheaper grades of vehicles, giving them the well-known advantage of the rail with but a slight addition in cost, as will be hereinafter more particularly set forth.

Referring to the accompanying drawings, which are made a part hereof, and on which similar letters of reference indicate similar parts, Figure 1 is a front elevation of a dash-board provided with my improved rail; Fig. 2, a horizontal section through the same on the dotted line 22, the central portion being broken out and the ends being shown on an enlarged scale; Fig. 3, a view similar to the top portion of Fig. 1, the rail being formed longitudinally adjustable; Fig. 4, a similar view showing the top part of the rail dispensed with; and Fig. 5, a detail view looking to the left from the dotted line 55 in Fig. 1.

In said drawings, the portions marked A represent the dash-board, and B the rail. The dash-board A is or may be of any ordinary or desired construction, and needs no special description. The rail B is mounted on the top edge of the dash-board, extending along the edge and down a short distance on each end to form handles, as is usual. It is supported and

secured in position by the supports B' on the top and B² on the ends. Said supports B' are sufficient in number to properly support the rail from the top of the dash, two, as shown, usually being sufficient. They are preferably formed integrally with said rail, extending down therefrom far enough to support said rail the desired height from the edge of said dash-board. Two lips, b', are formed on their lower ends, which extend down on each side of the top edge of the dash to a point just below the center of the bulge therein, (see especially Fig. 5,) and thus after the rail has been put in position a slight blow on these points operates to bend them in under said bulge and aid in securing the rail in position. Said supports B² are clamped to the ends of the dash-board at one end, and have the lower ends of the rail secured to their outer ends. The clamp part preferably consists of two jaws, b², which extend back on each side of the end piece of the dash-board frame to the rear thereof, and are provided with bolt-holes in their ends for the bolts b³, which pass through said holes and the dash-board, and, by means of the nuts b⁴, tightly clamp said jaws to said end piece and secure said support in position. At the right in Figs. 1, 2, and 4 I show a hinge, b⁵, formed in one jaw of the clamp, which renders it more flexible and easier to clamp; but, as will be readily understood, the jaws can be readily sprung together when formed as shown at the left in said figures, especially when formed from malleable iron or some similar material. I do not therefore desire to limit myself to any specific form of clamp. In their outer ends the supports are preferably provided with vertical holes, through which the lower ends of the rail are inserted, they being secured therein by nuts b on their lower ends, as shown. As will be readily seen, these supports might be formed in piece with said rail or secured thereto in any other manner without departing from my invention; but I regard the construction shown as preferable, as by means of the nuts b the rail can be drawn down very tightly upon the top edge of the dash, and thus be made very secure and rigid in position.

In Fig. 3 I show the rail formed in two parts

adapted to screw together in the central portion, thus rendering it adjustable to dash-boards of various lengths. In making new vehicles, this of course would not be necessary, as the 5 rail would then be made of the proper length at first; but by this construction they can be easily and quickly applied to any vehicle without any fitting or extra expense.

In Fig. 4 I show the top part of the rail dispensed with, and only the ends attached by my improved means to form handles. By this construction a rail is provided not only much cheaper to put on, but one that is also easily detached, when desired, as, when the plating 15 becomes worn off, it can be at once removed, replated, and readjusted in position without injuring the dash in any manner, thus making a very desirable as well as cheap rail.

I am aware that supplemental dash-boards 20 have been secured to the dash-board proper by being clamped to the top edge thereof, and said dash-board thus rendered more effective; but I do not regard this as a substitute for my invention, which is equally applicable to and desirable 25 on said supplemental dash-board when used as on the dash-board proper. As will be readily seen, if at any time it is desired to use such supplemental dash-board on a dash-board provided with my rail, said rail can be 30 readily removed, placed upon said supplemental dash-board, and the whole put in position.

Having thus fully described my said invention, what I claim as new, and desire to secure 35 by Letters Patent, is—

1. The combination, with a dash-board consisting of the ordinary metallic frame and leather covering, of a detachable rail provided with supports having clamps, whereby it is secured to the finished edges of said dash-board and held free therefrom, substantially as shown and described. 40

2. The combination, with the dash-board A, of the rail B, provided with the supports B', said supports B', engaging with the top edge of said dash-board, and the supports B², engaging with the ends of said dash-board at one end and being secured to the ends of said rail at the other, substantially as set forth. 45

3. The combination of the dash-board A, 50 rail B, supports B', and supports B², said supports B² having clamps formed on one end thereof, one jaw of which is provided with a hinge, substantially as set forth.

4. The combination, with a dash-board, of a 55 detachable rail constructed of two parts which are adjustable upon each other and provided with clamps, whereby it can be secured to or removed from the finished dash-board, substantially as set forth. 60

In witness whereof I have hereunto set my hand and seal, at Indianapolis, Indiana, this 7th day of September, A. D. 1885.

ROBERT W. LOGAN. [L. S.]

In presence of—

E. W. BRADFORD,
CHARLES L. THURBER.
